UNITED STATES PATENT OFFICE.

OLIVER GERRISH, OF BENICIA, CALIFORNIA, ASSIGNOR TO KULLMAN, SALZ & CO., OF SAN FRANCISCO, CALIFORNIA, A CORPORATION OF CALIFORNIA.

HIDE-PROTECTOR ATTACHMENT FOR FLESHING MACHINES.

Application filed November 17, 1924. Serial No. 750,257.

To all whom it may concern:

Be it known that I, OLIVER GERRISH, a citizen of the United States, residing at Benicia, in the county of Solano and State 5 of California, have invented certain new and useful Improvements in Hide-Protector Attachments for Fleshing Machines, of which the following is a specification.

In the tanning of hides and their preparation for use, one step in the treatment consists in what is termed fleshing.

Machines for fleshing hides are purchasable on the open market.

The operation of fleshing is well known, 15 and the object of the present invention is to provide a guard or protecting member for use in connection with a fleshing machine which will prevent the grain side of the hide from contacting with the fleshing cylinder while the hide is being placed in the fleshing machine, thereby overcoming the liability of the grain side of the hide becoming cut, scratched or otherwise damaged in its treatment within the fleshing machine.

20 The invention consists primarily in a movable guard designed for positioning to lie between the fleshing cylinder and the hide receiving and feed rolls, at such time as the latter are in a position to receive a hide to be treated.

The invention consists further in means for removing the hide protecting guard to inoperative position during such time as the positioned hide to be fleshed is fed to the 35 fleshing cylinder.

The invention further consists in providing operating means for the protecting guard for automatically moving the same to cylinder protecting position at such time as 40 the hide receiving and feeding means are in a position to receive a new hide.

With the above mentioned and other objects in view, the invention consists in the novel construction and combination of parts 45 hereinafter described, illustrated in the accompanying drawings and pointed out in the claims hereto appended, it being understood that various changes in the form, proportion, size and minor details of construction within the scope of the claims may be resorted to without departing from the spirit or sacrificing any of the advantages of the 50 invention.

In the drawings, wherein I have illustrated in dotted lines the conventional essential outline of a fleshing machine— 55

Figure 1 illustrates the fleshing machine parts in open or inoperative position, the guard being illustrated in heavy lines and in a position to preclude contact of the hide 60 with the fleshing cylinder.

Figure 2 is a view similar to Figure 1, illustrating the parts of the fleshing machine in closed or operative position and the guard removed or retracted, admitting 65 of the fleshing cylinder working on the positioned hide as the same passes over the rubber feed roll.

Figure 3 is a view in front elevation with the essentials of my invention illustrated 70 in heavy black lines, the parts being in a position corresponding to that illustrated in Figure 1.

The main structure of the fleshing machine will be briefly described, such description being sufficient to enable the attachment of my improved protecting guard to such apparatus, and while the drawing illustrates a Whitney fleshing machine, and the specification sets forth a Whitney fleshing machine, it is to be understood that this present guard is designed for use in connection with fleshing machines generally, the embodiment of the Whitney fleshing machine being for illustrative purposes. 85

In the drawings, the numerals 1 indicate the fleshing machine end frames between which are rotatably mounted a fleshing cylinder 2 of the well known type. A power shaft 3 is rotatable at its end in bearings 90 in the end frames 1, Fig. 3, and adjacent its ends the same carries cranks 4, the ends of which are connected through links 5 with the lower ends 6 of levers 7, the levers being fulcrumed as at 8 to the end frame members 95 1, as in Figs. 1 and 2 of the drawings.

The commonly termed rubber roll 9 of the fleshing machine is journaled at its opposite ends, as at 10, in the levers 7 above the fulcrum point 8, and at their extreme upper ends the levers have pivotally connected therewith the frame members 11, between the free ends of which are rotatably mounted a well known form of fleshing machine 100 pinch roll 12.

At a point above the bearing points of the

fleshing cylinder 2 are pivotally mounted, as at 13, to the end frames 1, the feed roll frames 14, in which are journalled the opposite ends of a feed roll 15 of the type commonly used in fleshing machines. The free ends of the frames 14 ride on and are guided by the shaft portions of the rubber roll 10, and the pinch roll 12 rests on and is guided by the upper surface of the free ends of the feed roll frames 14, as in Fig. 1.

The pinch roll when in operative position is forced into frictional contact with a conventional presser foot 16 normally pressed downwardly by springs 17. A water supply pipe 18 having a discharge head 19 extending parallel with and above the fleshing cylinder 2 supplies water to the hide as the same is being fleshed.

With the conventional construction of the fleshing machine above described is associated my present invention, consisting of a protecting means for the hide and the same includes a protecting guard or plate 20 disposed parallel with the fleshing cylinder 2 and guided at its ends to move in an upward inclination to lie between the rubber roll 10 and the fleshing cylinder 2 by suitable guide members 21, Fig. 3, carried by the end members 1. Fulcrumed to brackets 22 on the members 20, as at 23, are the upper ends of operating rods 24, terminating at their lower ends in split cam rings 25. The cam rings each encircle a guard operating cam 26 mounted respectively near the opposite ends of the shaft 3 and disposed with their peak at substantially right angles to the peak of the crank 4.

Carried by the discharge head 19 is a fixed guard 27 overlying the fleshing cylinder 2 and with the free edge of which the upper edge of the member 20 is adapted to contact, Fig. 1, when in its raised or operative position.

The shaft 3 is operated by any suitable manual mechanism and the rolls 12, 15 and 10 are caused to rotate in the direction of the arrows, by any suitable mechanism, power being imparted to the fleshing cylinder 2 in the direction of the arrow, Fig. 1.

50 The device operates in the following manner:—

With the parts in position, as in Fig. 1, the hide to be fleshed is picked up in the center by the operator, midway between the head and tail; this causes the hide to fall into a folded position with the grain-side of the hide outward. The operator then places or throws the hide on the pinch roll 12 with a portion of it dropping onto contact with the rubber roll 9. The upper fold is then thrown over into the machine, so that the hide will assume an unfolded position, which movement causes the grain side of the hide to be momentarily exposed and during such exposing, the guard 20 lying between

the roll 9 and the cylinder 2 precludes the knives of the cylinder from injuring the face of the hide.

The edge of the hide which has been thrown over assumes a perpendicular position, and when the main body portion of the hide has been adjusted, the operator actuates the shaft 3, which causes the parts to move from a position in Fig. 1 to that in Fig. 2, the guard 20 exposing the fleshing cylinder 2 and the rubber roll 9 moving the hide to be engaged by the fleshing cylinder 2.

It will be observed that when the pinch roll, rubber roll and feed roll are in the position indicated as in Fig. 1, that the guard 20 is elevated to preclude contact of the hide with the surface of the cylinder 2, and that when the parts are moved into operative position, the guard 20 is lowered, as the protection of the hide is no longer required.

I claim:—

1. In combination with a fleshing machine including a fleshing cylinder, means for receiving a hide to be fleshed and for feeding the same to the cylinder, means for moving the hide receiving and feeding means into and from operative position relatively to the fleshing cylinder, a hide protecting guard, and means for moving the guard to overlie the cylinder.

2. In combination with a fleshing machine including a fleshing cylinder, means for receiving a hide to be fleshed and for feeding the same to the cylinder, means for moving the hide receiving and feeding means into and from operative position relatively to the fleshing cylinder, and a hide protecting guard movable between the cylinder and the hide receiving and feeding means when the latter is in inoperative position.

3. In combination with a fleshing machine including a fleshing cylinder, means for receiving a hide to be fleshed and for feeding the same to the cylinder, means for moving the hide receiving and feeding means into and from operative position relatively to the fleshing cylinder, a hide protecting guard adapted to overlie the cylinder, and a second hide protecting guard movable between the cylinder and the hide receiving means when the latter is in inoperative position.

4. In combination with a fleshing machine including a fleshing cylinder, means for receiving a hide to be fleshed and for feeding the same to the cylinder, means for moving the hide receiving and feeding means into and from operative position relatively to the fleshing cylinder, a hide protecting guard, and means for moving the same between the cylinder and hide receiving means simultaneously with the movement of the latter into inoperative position.

5. In combination with a fleshing machine

including a fleshing cylinder, means for receiving a hide to be fleshed and for feeding the same to the cylinder, means for moving the hide receiving and feeding means into and from operative position relatively to the fleshing cylinder, a hide protecting guard movable into and from operative position between the cylinder and hide receiving means, and operating means for the guard connected with the hide receiving means whereby said guard and hide receiving means alternate in their movement into operative position.

6. In combination with a fleshing machine including a fleshing cylinder, means for receiving a hide to be fleshed and for feeding the same to the fleshing cylinder, and a hide protecting guard movable into operative position between the cylinder and the hide receiving and fleshing means to preclude

contact of the cylinder with the hide, and means for moving said guard into and from operative position.

7. In combination with a fleshing machine including a fleshing cylinder, means for receiving a hide to be fleshed and for feeding the same to the fleshing cylinder, means for moving the hide receiving and feeding means to and from the fleshing cylinder, a hide protecting guard disposed longitudinally of the cylinder, guides for receiving the opposite ends of the guard, a rotary shaft, and cam mechanism between the shaft and the guard for causing a movement of the guard to lie in advance of the fleshing roll when the hide receiving and feeding means are in inoperative position.

In testimony whereof I have signed my name to this specification.

OLIVER GERRISH.
